DESIGN FOR AN EMBROIDERED FABRIC

Joseph Bernstein, New York, N. Y.

Application December 18, 1942, Serial No. 109,060

Term of patent 3½ years

To all whom it may concern:

Be it known that I, Joseph Bernstein, a citizen of the United States, residing at New York, in the county of New York and State of New York, have invented a new, original, and ornamental Design for an Embroidered Fabric, of which the following is a full, clear, and exact description, reference being had to the accompanying drawing, forming a part thereof.

In the drawing:

Fig. 1 is a plan view of an embroidered fabric, showing my new design.

Fig. 2 is an enlarged view of a portion of Fig. 1 approximately within the dot and dash area.

I claim:

The ornamental design for an embroidered fabric, as shown.

JOSEPH BERNSTEIN.
